Primary Examiner — Susan Bennett Hattan*Assistant Examiner* — Rebecca Tsehay(74) *Attorney, Agent, or Firm* — Woods Oviatt Gilman LLP; Katherine H. McGuire, Esq.(57) **CLAIM**

I claim the ornamental design for an electric hair dryer, substantially as shown and described.

DESCRIPTION

FIG. 1 is a front perspective view of an electric hair dryer showing my new design;

FIG. 2 is a rear perspective view of FIG. 1;

FIG. 3 is a right-hand side elevation view of FIG. 1;

FIG. 4 is a left-hand side elevation view of FIG. 1;

FIG. 5 is a top plan view of FIG. 1;

FIG. 6 is a front elevation view of FIG. 1;

FIG. 7 is a rear elevation view of FIG. 1; and,

FIG. 8 is a bottom view of FIG. 1.
